ACOUSTIC TILE

Dominic D'Eustachio, Port Allegany, Pa., assignor to Pittsburgh Corning Corporation, Pittsburgh, Pa., a corporation of Pennsylvania

Application April 16, 1954, Serial No. 423,771

5 Claims. (Cl. 181—33)

This invention relates to acoustic tiles, i.e. tiles adapted for lining the walls and ceilings of rooms in order to deaden or absorb sound.

Various sound absorbing materials have been used in the past. It is well known that normal acoustical material and especially tile suitable for lining walls and ceilings are deficient in sound adsorption at frequencies below 500 cycles per second. Porous material containing intercommunicating cells or pores as, for example, bonded and compressed cellulose fibers, although suitable for absorbing higher frequency sound waves, are not suitable for absorbing low frequency sound waves such as those having frequencies below 500 cycles per second unless such sound absorbing material is quite thick. For example, as much as 12 inches may be required to absorb 100 cycles effectively. Thus, such materials are not suitable for use in relatively thin tiles.

Tiles made according to my invention will efficiently absorb sound waves having frequencies well below 500 cycles per second, also high frequency sound waves, and the tiles may be relatively thin, say not more than 1 or 2 inches in thickness.

In the accompanying drawings which illustrate a preferred embodiment of my invention,

Figure 1 is a plan view of a tile;

Figure 2 is a horizontal section taken on the line II—II of Figure 1; and

Figures 3—6 are charts showing curves obtained by plotting average sound absorption coefficient against frequency.

Referring more particularly to the accompanying drawings, the tile indicated generally by the reference numeral 2 is made of glass having pores or intercommunicating cells. It has a front face 3 adapted to be exposed to the sound to be absorbed and a rear face 4 adapted to be secured to a wall or ceiling to line it. The tile is provided with a resonant chamber 5 opening from the rear face of the tile and terminating short of the front face. One or more apertures 6 lead from the resonant chamber to the front face of the tile. In the embodiment shown, four such apertures 6 are employed but a single aperture or any other number of such apertures could be used provided they were dimensioned according to the invention as hereinafter described. The front face 3 of the tile is provided with pockets 7 extending only part way through the tile. These pockets preferably are spaced throughout substantially the entire extent of the front face.

In accordance with my invention, the dimensions of the resonant chamber 5 and the aperture or apertures 6 are correlated in such manner as to effectively absorb sound having frequencies between 50 and 500 cycles per second. In the specific embodiment of my invention which is illustrated in Figures 1 and 2, the tile is 12 inches long and 12 inches wide and has a thickness from its front face 3 to its rear face 4 of 1 1/4 inches. The cylindrical resonant chamber 5 is 11 inches in diameter and 1/4 inch deep. The apertures 6 are 1/4 inch in diameter and 1 inch long. In accordance with my invention, the dimensions of the resonant chamber 5 and the aperture or apertures 6 are so correlated that when the formula

$$f = \frac{2160A}{(vV)^{1/4}}$$

wherein

f =frequency of maximum absorption in cycles per second
 A =cross sectional area of aperture in square inches

v =volume of aperture in cubic inches

5 V =volume of resonant chamber in cubic inches

is applied to the tile, the factor f has a value between 50 and 500.

In the tile having the dimensions as given above,

10 $V=23.8$ cubic inches

$A=0.048$ square inches (total area of 4 apertures)

$v=0.048$ cubic inch

Applying these values to the above formula, the value

15 of f is approximately 100 which means that the sound absorbing capacity of the tile due to the provision of the resonant chamber 5 and apertures 6 will be a maximum at a frequency of about 100 cycles per second (C. P. S.). The frequency of maximum absorption can 20 be easily changed over the range 50 C. P. S. to 500 C. P. S. by changing the number or size of the apertures 6 or by changing the depth of the resonant chamber 5.

Although the tile can be made of any suitable porous material, it is preferred that it be made of vitreous material, particularly glass. The glass or other material should be porous, i. e., it should be constituted of pores or intercommunicating cells. Cellular glass can be made by heating a powder mixture of glass and a suitable cellulating agent such as lampblack to a temperature sufficient to sinter the glass and form gas which produces closed cells in the glass. If it is desired to use cellular glass in forming the tile of the present invention, the cells should be opened by some suitable means, as, for instance, by the method disclosed in my Patent No. 2,596,659, granted May 13, 1952, according to which the cellular glass is subjected to fluid pressure sufficient to open the cells without otherwise breaking down the structure. However, a product having intercommunicating pores or cells can be made in the first instance by known methods and such product can be used in making my acoustic tile.

45 The resonant chamber 5 need not be cylindrical but can be made of any other desired shape. However, it is preferred to make it cylindrical because of facility of manufacture.

Figure 3 shows curves obtained by plotting average sound absorption coefficient against frequency. Curve 1 applies to low frequencies, curve 2 to high frequencies and curve 3 is a composite of curves 1 and 2. A tile 50 having the characteristic shown by curve 1 can be made by employing a resonant chamber 5 and an aperture or apertures 6 of the dimensions previously specified. This curve shows that the maximum sound absorption is obtained at a frequency of about 100 C. P. S., although the absorption is effective over a considerably greater range of frequencies. As previously stated, the peak or maximum absorption frequency can be shifted to the right or left from that shown in Figure 3 by changing the number or size of the apertures 6 or by changing the depth of the resonant chamber 5.

60 By making the tile of porous material having intercommunicating pores or cells, it will effectively absorb high frequency sound waves. A tile having the characteristics shown by curve 2 can readily be obtained by

65 making the tile out of a porous material but such means is relatively ineffective in absorbing sound waves of low frequency. In accordance with my invention, effective sound absorption at low frequencies is obtained by the resonant chamber 5 and aperture or apertures 6, whose dimensions are so correlated as to produce effective sound absorption at low frequencies. My tile also is made of porous material having intercommunicating pores or cells whereby it is effective in absorbing sound waves of high frequency. Curve 3 in Figure 3 is a composite of curves 1 and 2.

70 It can be seen that by combining curves 1 and 2 to produce curve 3, effective sound absorption can be obtained over a wide range of frequencies. Thus, in accordance with my invention, tiles having effective sound absorption over a wide range of frequencies can be obtained by using in combination a 75 porous material which is effective at high frequencies

and forming the porous material with the resonant chamber 5 and apertures 6 so dimensioned as to be effective in absorbing sound waves of low frequency.

Figure 4 is similar to Figure 3 except that it shows the characteristics of a tile in which the resonant chamber 5 and apertures 6 are so correlated that the tile has a maximum sound absorption at a frequency of about 200 C. P. S. This can be accomplished by providing sixteen $\frac{1}{8}$ inch apertures in place of the four apertures 6 shown in Figures 1 and 2.

It is my intention to tune the resonant chambers 5 in the tiles to different frequencies and to mix the tiles so tuned in applying them to a wall or ceiling in order to broaden the sound absorption range. As an example, tiles with a resonant chamber 11 inches in diameter and $\frac{1}{4}$ inch deep might be divided into four groups: the first group having four $\frac{1}{8}$ inch apertures, the second group eight $\frac{1}{8}$ inch apertures, the third group sixteen $\frac{1}{8}$ inch apertures and the fourth group having thirty-two $\frac{1}{8}$ inch apertures communicating between the chamber and the front surface. The chambers would then be tuned to 100 C. P. S., 140 C. P. S., 200 C. P. S. and 280 C. P. S., respectively. The result of using such an arrangement of tiles in which the tiles of the different group are arranged at random is shown in Figure 5. The same result can be attained by including in an installation tiles having resonant chambers of different depths or by a combination of resonant chamber depth and number of apertures. It should be noted that an installation having the characteristic of Figure 3 can be changed in the field after installation to that shown in Figure 5 merely by piercing the proper number of pockets 7 (already in the tile) so that they become apertures communicating with the resonant chamber. Obviously, the process can also be reversed by plugging up some of the apertures with a suitable mastic, for example, ordinary glazing compound.

Figure 6 represents an installation in which one-half of the tiles are tuned to a maximum sound absorption of 100 C. P. S. and the other half of the tiles to a maximum sound absorption frequency of 200 C. P. S. Such arrangement can be readily made by providing half of the tiles with four apertures 6 as shown in Figures 1 and 2 and the other half of the tiles with sixteen such apertures.

The employment of the pockets 7, although preferred, is not essential to the invention. They do, however, considerably increase the effectiveness of the tile in absorbing sound waves of high frequency in that they provide paths with great frictional loss for the rapidly

50

pulsating air (sound waves) which impinge on the tile. Another purpose of these pockets is to permit sound waves to enter the porous interior of the tile after the exterior surface has been painted or otherwise covered with a decorative finish.

Tiles made according to my invention will effectively absorb sound waves down to frequencies as low as 100 cycles per second and also high frequency sound waves even though they do not exceed 2 inches in thickness 10 which, of course, is a distinct advantage as compared with a tile which must be made much thicker in order to accomplish this result.

The invention is not limited to the preferred embodiment but may be otherwise embodied or practiced within 15 in the scope of the following claims.

I claim:

1. An acoustic tile made of porous material having intercommunicating pores or cells, said tile comprising a front face adapted to be exposed to the sound to be 20 absorbed, a rear face adapted to be secured to a wall or ceiling, a resonant chamber opening from the rear face of the tile and terminating short of said front face, at least one aperture leading from said resonant chamber to said front face, the dimensions of said resonant 25 chamber and aperture being so correlated that when the formula

$$f = \frac{2160A}{(vV)^{\frac{1}{2}}}$$

30 wherein

f =frequency of maximum absorption in cycles per second
 A =cross sectional area of aperture in square inches

v =volume of aperture in cubic inches

V =volume of resonant chamber in cubic inches

35 is applied to the tile, the factor f has a value between 50 and 500.

2. A tile according to claim 1, wherein the tile is made 40 of vitreous material.

3. A tile according to claim 1, wherein the tile is made of glass.

4. A tile according to claim 1, wherein the thickness 45 of the tile is not over 2 inches.

5. A tile according to claim 1, wherein the tile is made of glass and wherein the front face of the tile is provided with pockets extending only part way through the tile.
